UNITED STATES PATENT OFFICE.

GEORGE GRUNWALD, OF BRONX, NEW YORK.

PORTABLE FOLDING CHAIR.

Application filed September 12, 1924. Serial No. 737,327.

This invention relates to chairs and has special reference to a portable folding chair.

One important object of the invention is to improve the general construction of devices of this character.

A second important object of the invention is to provide an improved form of folding chair wherein both the chair frame and the legs are housed in a tubular stand-
ard when the parts are collapsed.

A third important object of the invention is to provide an improved form of folding frame for the seat and back portions of such a chair.

A fourth important object of the invention is to provide improved means for holding the legs.

A fifth important object of the invention is the provision of an improved form of folding frame for the back of a collapsible chair of this type.

With the above and other objects in view as will be hereinafter apparent, the invention consists in general of certain novel de-
tails of construction and combinations of parts hereinafter fully described, illustrated in the accompanying drawings and specifically claimed.

In the accompanying drawings like char-
acters of reference indicate like parts in the several views, and:

Figure 1 is a front elevation of the chair completely expanded.

Figure 2 is a perspective view of the top part of the chair with the cloth for the seat and back removed and showing the frame fully expanded.

Figure 3 is a view similar to Figure 2 with the frame partly collapsed.

Figure 4 is a view of the device with the frame and legs fully collapsed and partially inserted in the tube.

Figure 5 is a section on the line 5—5 of Figure 1.

Figure 6 is a section on the line 6—6 of Figure 1.

Figure 7 is a detail showing the arrangement of the hubs in the housing tube, the arms and legs being broken off.

Figure 8 is a view similar to Figure 7 but showing a modification employing flanges for affording supplemental bearing surfaces for the arms and legs.

Figure 9 is a section through one of the front seat arm swivels. 55

Figure 10 is a view showing a modification of the swivel shown in Figure 9.

Figure 11 is a detail section showing the connection between the front brace bars.

Figure 12 is a perspective view of a slight 60 modification of the lower part of the invention.

In the embodiment of the invention herein disclosed there is shown a tubular casing comprising a housing tube 10 having a 65 lower cap 11 and an upper cap 12. In the present instance the tube 10 and caps are cylindrical and the latter are screwed on the tube but it will be obvious to any mechanic that these caps may be soldered or brazed 70 on and that both the tubes and caps may be of other shape than cylindrical, the particular shape not in any way affecting the essential features or operation and function 75 of the device.

The lower cap 11 is provided with a series of bayonet slots 13 having extensions 14 leading from the bottom edge of the cap 11 toward the center thereof. Slidable in the bottom end of the tube 10 is a plunger 80 15 having on its under surface pairs of spaced lugs 16 through which pass pivot pins 17. Legs 18 have their inner ends pivoted on these pins between respective lugs and project through the bayonet slots 13 or 85 their extensions 14 in accordance with the expanded or collapsed position of said legs. These legs may be provided with downwardly turned feet 19 but it is to be understood that the legs may be of any desired 90 shape.

In the upper end of the tube 10 is slidably mounted a plunger 20, similar to the plunger 15, and like it, provided with pairs of spaced lugs 21 having pivot pins 22 95 carrying arms 23 extending through the central opening 24 of the upper cap 12, the latter being provided with notches 25 wherein the arms engage when unfolded. Two of these arms project forwardly and, in the form shown in Figure 9, have reduced ends 26 whereon are journaled the sleeves 27. These sleeves are provided with forked outer extremities 28 and between the arms of each fork is pivoted one end of a 100 brace bar 29, the free ends of the two brace 105

bars being connected by a link 30 pivoted to the respective brace bars and having bevelled ends to prevent movement of the brace bars beyond predetermined positions.

5 Each of the remaining arms 23 has its free end laterally flattened and provided with an upwardly extending finger 31. At 10 32 are lower back bars each having a fork 33 at its lower end which straddles a respective flattened arm end and is pivotally connected thereto in such manner as to rest against the respective finger upon the device being erected. The pivots connecting these members are shown at 34 and on each of 15 these pivots is a hook 35. Similarly, on each forward arm 23, at its free end adjacent the brace bar, is a hook 36. By means of these hooks a seat 37 may be supported on said arms, the latter resting, when unfolded, in 20 the notches 25. On the free end of each lower back bar is pivoted an upper back bar 38, the pivot point being slightly above the lower end so that a lug 39, projecting from the lower end portion of the upper 25 back bar may, when the latter is erected, engage the side of the respective lower back bar to limit rotative movement of the upper bar. In order to permit the folding of members 32 and 38 without interference, the 30 pivot connection between member 38 and the member 32, on the one hand, and the pivot connection between the member 32 and the arm 23, on the other hand, are so related that the planes of pivotal movement form 35 an angle with each other. On these upper bars is fitted a seat back 40 having pockets 41 wherein said upper bars are received.

As shown in Figure 8 the upper and lower caps may be provided with flanges 42 to afford broader resting surfaces for the legs 40 and arms.

Also, as shown in Figure 10 a second type of joint may be used between the front arms and brace bars. In this joint arm a swivel eye 43 is pivoted to each front arm 23 and the respective brace bar is pivoted to said eye.

In order to understand the operation of this device let it be supposed that the same 50 is set up. Then, to collapse the device the legs may be swung to the left until they reach the vertical portion of the bayonet slots. They may then be folded toward each other and slipped up into the tube as 55 shown in Figure 3. Also the seat may be unhooked and the back slid off the upper back frame members; these may then be turned down on the lower back frame members and the two folded on the back arms. 60 At the same time the brace bars may be turned as a unit about their pivot connections, and by moving the front frame members upwardly out of the notches 25 and toward the axis of the tube 10 may be turned 65 down on the front frame members, as indi-

cated in Fig. 4. The back arms, and their attachments may then be turned up and the whole slid into the tube, a partition 44 limiting the movements of both the legs and the folded arms. Obviously in setting up 70 the reverse operation is performed.

In Figure 12 a modification has been shown wherein the legs 19 are provided with brace members 19^a, pivoted to the legs and connected together by central plate 19^b. 75 This prevents the legs from spreading too much and may be used when needed.

There has thus been provided a simple and efficient device of the kind described and for the purpose specified. 80

It is obvious that minor changes may be made in the form and construction of the invention without departing from the spirit thereof. It is not, therefore, desired to confine the invention to the exact form herein 85 shown and described, but it is desired to include all such as properly come within the scope claimed.

Having thus described the invention, what is claimed as new, is: 90

1. In a folding chair, the combination of a tubular casing having at one end a plurality of slots extending in axial direction from the edge of the casing and then in circumferential direction, a disc-like body in the casing movable lengthwise thereof and legs pivoted on said body for angular movement in radial planes, said slots being of a width to receive the legs. 95

2. In a folding chair, the combination of a tubular casing having at one end a plurality of notches, a disc-like body in the casing movable lengthwise thereof, arms pivoted on said body for angular movement in radial planes, the notches being adapted to receive the arms, means on the arms for connection with a seat and bracing mechanism between two of said arms, comprising two members connected thereto, one to each arm for universal movement relatively thereto, means defining a pivotal connection between said members and means constructed and arranged to co-operate with the two members to restrain relative pivotal motion thereof in one direction. 105

3. In a folding chair, the combination of a tubular casing having at one end a plurality of notches, a disk-like body in the casing movable lengthwise thereof, arms pivoted on said body for angular movement in radial planes, the notches being adapted to receive the arms, means on the arms for connection with a seat and means connected with two of said arms to form the back of the chair, said means comprising a pair of frame members, one pivotally connected to each arm, means for limiting the extent of the pivotal movement, a second pair of frame members, one pivotally connected to the free end of each of said frame members 110

and means for limiting the extent of the pivotal movement of the second frame members.

4. A construction according to claim 3,
5. wherein the pivot connection between each of the second frame members and the first frame members is so disposed that the plane of the pivotal movement forms an angle

with the plane of the pivotal movement between the respective first frame members ¹⁰ and the corresponding arms to which they are connected.

In testimony whereof he hereunto affixes his signature.

GEORGE GRUNWALD.
